DRILLING MACHINE

Charles A. Hirschberg, Mountain Lakes, N. J.,
assignor to Worthington Pump and Machinery
Corporation, New York, N. Y., a corporation of
Virginia

Application February 19, 1936, Serial No. 64,789

2 Claims. (Cl. 121—8)

This invention relates to percussive tools or drilling machines of the type commonly known as stoppers, wherein the pressure fluid-operated drill is gradually fed to its work by a feed cylinder employed in conjunction with the drill and usually in substantial alignment therewith, and particularly to tools of this type which embody a tube through which fluid passes for cleaning the drill holes.

10 Due to the manner in which such drills operate the cleaning fluid-conducting tube often becomes fouled, breaks or otherwise is affected so as to require its replacement.

15 It is an object of the present invention to provide a tool of this type in which such cleansing fluid-conducting tube may be readily and easily removed and repaired or replaced at the place where tool is working, without disengaging any of the working parts of the tool; without exposing any of the working parts to mine or tunnel dust which might impair the operation of the tool, and in a minimum space of time with minimum effort on the part of the operator.

20 With these and other objects in view, as may appear from the accompanying specification, the invention consists of various features of construction and combination of parts, which will be first described in connection with the accompanying drawings, showing a drilling machine 30 of the preferred form embodying the invention, and the features forming the invention will be specifically pointed out in the claims.

In the drawings:

Fig. 1 is a side elevation of the improved drilling machine.

Fig. 2 is an enlarged detail in side elevation showing a different side of the tool or drilling machine.

Fig. 3 is a horizontal section on the line 3—3 of Fig. 1, looking upwardly.

Fig. 4 is a longitudinal section taken on the line 4—4 of Fig. 2 and showing the tool in open position in dotted lines.

45 Referring more particularly to the drawings, the improved drilling mechanism or percussive tool includes the hammer engine 1 of any approved type, which operates the drill steel 2 for drilling, and the feed mechanism 3 which operates to feed the drill steel 2 and the entire drilling machine to its work.

50 The hammer engine 1 may be of any approved construction including the cylinder 4 which is connected in any suitable manner to the valve block 5. The valve block 5 carries a throttle valve 6 which controls the feeding of the oper-

ating fluid to the hammer engine 1 and also controls the feeding of the operating pressure fluid to the cylinder 7 of the feed mechanism 3 for acting upon the piston 8 which is mounted for reciprocatory movement in the feed cylinder 7 5 and this piston acting through the anchoring point 9 and a surface or abutment 10 opposite to the surface which is being drilled, will force the drill steel 2 to its work and apply a constant feeding pressure to the cylinder 3 and the hammer engine 1 as is usual in the construction and operation of stoppers or drilling machines of this type.

10 The drilling machine includes a tube 11 through which cleansing fluid, either water or air under 15 pressure, is delivered through the drill steel 2 for the purpose of cleaning the drill hole. The tube 11 is held in place in the valve block 5 by a removable nut 12 and its companion structure, as clearly shown in Fig. 4 of the drawings. The 20 tube 11 receives the cleansing fluid from a port 13, annular passage 14 and the duct or passage 15.

15 The pressure fluid for operating the feeding mechanism 3 passes from the throttle valve 6 25 through a passage 16 formed in the valve block 5, a passage 17 formed in the head 18 of the feed cylinder 7, and through a suitable horizontal passage 19 into the cylinder 7.

20 The tube 11 which conducts the cleansing fluid 30 to the drill hole frequently requires replacement or repair and for the purpose of facilitating such repair or replacement of this tube without disturbing any of the operating parts of the drilling machine and without subjecting such parts 35 to contact with tunnel or mine dust, the drilling machine is made in two sections with a tight-fitting metal-to-metal joint between the under-surface of the valve block 5 and the upper surface of the head 18 of the feed cylinder 7. The 40 two sections of the drilling machine are swingably connected by means of an eye bolt 20 which is in turn swingably mounted upon a cross bolt 21 carried by suitable ears or bosses 22 formed 45 on the valve block 5. A substantial U-shaped bracket 23 is formed on the head 18 of the cylinder 7 and its upstanding arms 24 are provided with substantially oval-shaped slots 25 through which the bolt 21 extends, thus providing a firm 50 solid swingable connection between the hammer engine 1 and the feeding mechanism 3 so that the hammer engine may be swung into an open position as shown in dotted lines in Fig. 4 55 of the drawings, to permit ready removal of the 55

nut 12 and consequently ready and easy removal of the tube 11 either for repair or replacement.

A locking bolt 26 is pivotally connected by means of its eye 27 and a suitable bolt or pin 28 to ears 29 formed on the feed cylinder head 18. The locking bolt 26 swings between suitable locking ears 30 formed on the valve block 5 and is clamped tightly in place for locking the sections of the tool tightly together by means of the nut 31 which is threaded on the locking nut 26 and tightly clamps against the upper sides of the ears 30.

The U-shaped bracket 23, ears 22 and the ears 30, and the locking nut 26 are all arranged so that when the locking nut is in locking position the joint between the undersurface of the valve block 5 and the upper surface of the feed cylinder head 18 will be tight and the passages 16 and 17 in proper registration for delivering pressure fluid to the feed cylinder 7 of the feeding mechanism 3.

It will be understood that the invention is not to be limited to the specific construction or arrangement of parts shown but that they may be widely modified within the invention defined by the claims.

What is claimed is:

1. In a percussive tool, in combination, a valve block, a cylinder connected to the valve block, a cleansing fluid-conducting tube detachably en-

gaging the valve block and extending into said cylinder, a feed cylinder, a head on said feed cylinder, a substantially U-shaped bracket carried by said head, a pivoting bolt carried by said valve block and extending through the legs of said U-shaped bracket, an eye bolt rigidly carried by said bracket and having its eye engaged by said pivoting bolt, the legs of said U-shaped bracket provided with elongated openings to permit lateral movement of the pivoting bolt relative to the bracket.

2. In a percussive tool, in combination, a valve block, a cylinder connected to the valve block, a cleansing fluid-conducting tube detachably engaging the valve block and extending into said cylinder, a feed cylinder, a head on said feed cylinder, a substantially U-shaped bracket carried by said head, a pivoting bolt carried by said valve block and extending through the legs of said U-shaped bracket, an eye bolt rigidly carried by said bracket and having its eye engaged by said pivoting bolt, the legs of said U-shaped bracket provided with elongated openings to permit lateral movement of the pivoting bolt relative to the bracket, and a locking bolt swingably carried by the feed cylinder and engaging the valve block to lock the valve block and feed cylinder in working position.

CHARLES A. HIRSCHBERG. 30
